UNITED STATES PATENT OFFICE.

WILLIAM EXCELL BAKER, OF WEST NORWOOD, ENGLAND.

IRONING MACHINE.

Application filed January 19, 1921. Serial No. 433,499.

To all whom it may concern:

Be it known that I, WILLIAM EXCELL BAKER, a subject of the King of Great Britain and Ireland, residing at 62 Gipsy Road, 5 West Norwood, in the county of Surrey, England, have invented certain new and useful Improvements in Ironing Machines (for which I have filed application in Great Britain, No. 1935/17, Patent No. 113,140), 10 of which the following is a specification.

This invention relates to ironing machines of the type in which a flat iron of such a weight as will give the necessary pressure is employed and is caused to reciprocate over a fixed table, and it consists of an improved method of imparting the necessary motion to the iron and of reversing the motion of same, the object being to obtain a mechanism which is of simple construction, 20 is silent and smooth in running and reversing and which is easy to adjust and keep in working order.

A further object is to prevent damage to the machine in case the operator does not 25 reverse the movement of the iron before the limit of its travel in either direction is reached.

In the accompanying drawings which illustrate this invention:—

30 Figs. 1 and 2 are views in side elevation and plan of the improved machine.

Figs. 3 and 4 are broken views in front and end elevation—on an enlarged scale— 35 showing the operating and driving mechanism, and

Figs. 5 and 6 are broken views in end and front elevation respectively showing the construction of the clutch. Throughout the views similar parts are marked with like 40 letters of reference.

The improved driving mechanism comprises a belt or the like M which travels constantly in one direction over a pair of pulleys L and L located at a suitable distance apart and carried by shafts T running in bearings carried by a suitable frame X, 45 one of said pulleys being driven from any suitable source of power. Between the pulleys L and L is a bar A on which is mounted, so as to slide thereon, an arm G carrying two grip couplings forming a double clutch J by means of which said frame can be coupled either to the part of the belt travelling above the pulleys or to 50 the part of the belt travelling below the pulleys according to the direction in which

it is desired the frame should travel. The clutch J slides vertically in a suitable guide P carried by the arm G and the necessary rising or lowering movement to bring said 60 clutch into engagement with the band M either above or below the pulleys L and L is effected by a longitudinally arranged bar K which engages rollers R and R carried by the clutch J. A vertical or up and down 65 motion is imparted to the bar K either by a treadle W, or by a hand lever H, both of which operate through rods I and I located at each end of the machine.

The iron D which is of such weight that 70 it creates its own pressure, is coupled by a universal joint O to the arm G which carries brackets E and E which are adapted to slide on the bar A and thus allow the iron to travel over the table or board in 75 contact therewith.

Mounted on the frame of the machine near each end thereof are inclined planes V and V' which operate in conjunction with the rollers R to stop the travel of the iron D 80 and to effect a reversal of the direction of its motion at one end or both ends of its travel. The preferred construction is to so shape the inclined planes V and V' that the former operates to disengage the clutch 85 J from the upper part of the band and to engage it with the lower part of said band whereby the direction of travel of the iron is reversed and the latter operates to disengage the clutch J from the lower part of 90 the band M without engaging it with the upper part thereof whereby the iron is brought to a state of rest. At the end of the table or board C at which the plane V' is located is a stand S for the iron to rest 95 on when it is brought to a state of rest in this position.

What I claim is:—

1. In an ironing machine of the type in which a flat iron is caused to travel over 100 a fixed table, means for imparting a reciprocating motion to the iron comprising a band travelling around and between two pulleys and a clutch for coupling said iron to said band either above or below said 105 pulleys, and mechanism having no travelling movement relative to the table for actuating said clutch controlled by manual power.

2. In an ironing machine of the type in which a flat iron travels over a fixed table 110 the combination of mechanism for imparting reciprocating motion to said iron com-

prising a band travelling over and between two fixed pulleys to one of which the driving power is applied and a double acting clutch for coupling said iron to said band 5 either above or below said pulleys, of mechanism having no travelling movement in relation to said table for actuating said clutch by manual power, of means for automatically declutching the driving connection of said 10 iron when it reaches the limit of its travel in either direction.

3. In an ironing machine of the type in which a flat iron travels over a fixed table the combination of mechanism for imparting reciprocating motion to said iron comprising a band travelling over and between two fixed pulleys to one of which the driving power is applied and a double acting clutch for coupling said iron to said band 15 either above or below said pulleys, of mechanism having no travelling movement in relation to said table for actuating said clutch by manual power, of means for automatically reversing the direction of travel of said 20 iron as and when it reaches the limit of its travel in either direction.

4. An ironing machine comprising a weighted flat iron, a table over which the iron can travel, a band travelling around and between two pulleys, means for imparting motion to one or both of said pulleys, a clutch for coupling the iron to said band either 30 above or below said pulleys, mechanism for actuating said clutch by foot or hand, stops 35 for automatically declutching the driving connection of the iron when same has reached the limit of its travel in either direction in relation to the table, and a stand for receiving the iron when it is brought to rest 40 at one end of the table.

5. In an ironing machine of the type in which a flat iron travels over a fixed table the combination of mechanism for impart-

ing reciprocating motion to said iron comprising a band travelling over and between two fixed pulleys to one of which the driving power is applied and a double acting clutch for coupling said iron to said band either above or below said pulleys, of mechanism having no travelling movement in relation to said table for actuating said clutch by manual power, of means for automatically releasing the driving couple of said iron as and when it reaches the limit of its travel in either direction and for automatically engaging said coupling at one end of its travel so as to cause said iron to travel in the opposite direction.

6. In an ironing machine the combination of a table mounted on a suitable frame, a horizontally disposed bar carried by said frame, pulleys mounted on bearings carried by said frame, a driving pulley coupled to one of said pulleys, a band passing over and between said pulleys, a bracket adapted to slide on said bar, a double acting clutch carried by said bracket, a flat iron coupled to said bracket by a universal joint, of stationary hand or foot operated mechanism for actuating said clutch so as to cause it to engage said band either above or below said pulleys, of inclined planes carried by said frame, of rollers carried by said sliding bracket and adapted to co-operate with said inclined planes for the purpose of automatically reversing the direction of travel of said iron as and when it reaches the limit of its travel in one direction and to automatically stop the travel of said iron when it reaches the limit of its travel in the other direction, and of a stand located at one end of said table adapted to receive the iron when it is brought to rest at the limit of its travel in one direction.

WILLIAM EXCELL BAKER.
